UNITED STATES PATENT OFFICE.

WILLIAM D. FORSYTH, OF YOUNGSTOWN, OHIO, ASSIGNOR TO RAILWAY PRODUCTS CORPORATION, OF BUFFALO, NEW YORK, A CORPORATION OF NEW YORK.

DRAFT-GEAR.

1,130,388.

Specification of Letters Patent.

Patented Mar. 2, 1915.

Application filed December 4, 1913. Serial No. 804,680.

To all whom it may concern:

Be it known that I, WILLIAM D. FORSYTH, a citizen of the United States, residing in the city of Youngstown, county of Mahoning, and State of Ohio, have invented a new and useful Improvement in Draft-Gears, of which the following is a specification.

My invention relates to improvements in removable draft gears for railway cars.

10 The principal object of my invention is to provide a construction in draft gears which will enable some of the parts of the draft gears to be assembled in units convenient for the placing of them on the cars and all of 15 the parts to be readily removable with relation to one another.

My invention consists in the improved draft gear hereinafter specifically described and claimed.

20 In the accompanying drawing, Figure 1 is a plan view of my improved draft gear. Fig. 2 is a side view of Fig. 1 with parts removed. Fig. 3 is a view of the spring case in plan reduced in scale; Fig. 4 is a side 25 elevation of Fig. 3. Fig. 5 is a side elevation of the yoke reduced in scale. Fig. 6 is a plan view of Fig. 5. Fig. 7 is an end view 30 of the special follower-plate to be used with the improved draft gear reduced in scale. Fig. 8 is a side elevation of said improved follower-plate.

Like figures of reference refer to like parts throughout.

In the draft gear shown in the accompanying drawing, a draw bar 1 fits between the ends of a U-shaped yoke 2. Through holes 3 in the yoke 2 and a hole 5 in the draw bar 1 passes a removable pin 4 which secures the yoke to the draw bar. The draw 35 bar 1 and the yoke 2 are mounted in the usual way between the draft sills 6 of the car, and the draft sills 6 have cleats 7 riveted to them. Within the yoke 2 is removably mounted a spring case 9 which has two 40 compartments 10 therein. The compartments 10 have two of their longitudinal sides closed and two of said sides open, and said compartments are separated by a partition or abutment 11. In each compart-

ment 10 are two follower plates 8, one in 50 each end thereof. Each follower plate 8 has a central boss or projection 12 and two integral arms 13 which project from each side of the follower plate. The compartments 10 are wider than the yoke 2 so that above and 55 below the yoke there is a space through which the arms 13 of the follower plates 8 project beyond the yoke into engagement with the cleats 7 secured to the draft sills 6. In each compartment 10 between the 60 follower plates 8 therein is a spring 14, the ends of which fit over the bosses 12 of the follower plates.

The entire draft gear may be supported 65 between the draft sills of the car by any of the usual means, by strap or cleat, extending across the bottom, or otherwise, so that said draft gear is not permanently fastened to said sills, but the operation of the same is dependent upon the ends of fol- 70 lower-plates impinging against cleats 7 of the sills. Openings, 15, are provided in the draft sills 6 for the passage of the pin 4, which is retained in position by cotter pins passed through holes 16 in the ends of said 75 pin.

What I claim as my invention is:

In a draft gear, a U-shaped draft yoke, a draw-bar removably secured between the ends of said yoke, a spring case removably 80 mounted between the sides of said yoke and engaging the closed end of said yoke and said draw-bar said spring case having compartments therein which have two closed sides and two open sides, said open sides 85 facing said yoke, a pair of follower plates mounted in each of said compartments and having portions extending beyond said yoke, and springs between each pair of said follower plates.

In testimony whereof I have hereunto 90 subscribed my name in the presence of two subscribing witnesses.

WILLIAM D. FORSYTH.
